UNITED STATES PATENT OFFICE.

ROLAND H. STUBBS, OF WATERFORD, NEW YORK.

HEATING APPARATUS.

SPECIFICATION forming part of Letters Patent No. 518,798, dated April 24, 1894.

Application filed December 7, 1893. Serial No. 493,003. (No model.)

To all whom it may concern:

Be it known that I, ROLAND H. STUBBS, a citizen of the United States, residing at Waterford, county of Saratoga, and State of New 5 York, have invented certain new and useful Improvements in Heating Apparatus, of which the following is a specification.

My invention relates to such improvements and consists of the novel construction and 10 combination of parts hereinafter described and subsequently claimed.

Reference may be had to the accompanying drawings, and the letters of reference marked thereon, which form a part of this specification. 15

Similar letters refer to similar parts in the several figures therein.

The object of my invention is to provide a metal casting with a water or steam passage 20 therethrough by casting the metal around a thin pipe which forms a permanent hollow core and securing inlet and outlet coupling-sections directly to the casting in communication with the respective terminals of the core- 25 pipe. A cast-metal wall having a passage therethrough with convenient means for coupling water or steam-pipes in communication with its terminals has various uses, among them that of a water-heating and circulating 30 device, when the casting has a fire-surface. Various attempts have been heretofore made to provide a casting with such a passage and connections, by using a sand or other de- 35 structible core, which is expensive and un- 40 certain in results, and by inclosing a metal pipe in the casting with its ends projecting therefrom and coupling the inlet and outlet pipes upon such projecting ends. In pur- 45 suing the latter method, it was necessary that the inclosed pipe should be sufficiently heavy and strong to permit of coupling the connect- 50 ing pipes thereto, and the use of a thick and heavy pipe, made necessary by these require- 55 ments, added largely to the expense of manu- 60 facture and required so thick a wall to inclose the pipe that the casting was unavail- 65 able for general use, due to its great weight and bulk. In my improved construction, I 70 use as a core, a flexible pipe of sufficient 75 strength to withstand the casting operation, 80 but too thin to form a support for coupling 85 mechanism, and cast around the same a metal 90

wall of the desired form, and secure coupling-sections of suitable strength and thickness directly to the casting in communication with 55 the respective terminals of the thin core-pipe, which is allowed to remain in the casting.

The advantages derived from the use of a relatively thin core-pipe are many. Such pipe is less expensive than heavier and 60 stronger pipe, and is more easily bent and made to assume the desired form in the mold preparatory to casting the metal around the core. The thinness of the core-pipe wall also 65 enables me to bring the contents of such pipe, in use, nearer the heated surface, when the casting forms a fire-wall.

Figure 1 of the drawings is a view in central vertical section of a circular fire-pot embodying my invention, and adapted for use 70 as a water-heating-and-circulating device in a common form of heating stove. Fig. 2 is a horizontal section of a rectangular form of fire-pot made after my invention. Fig. 3 is a view of a piece of thin core-pipe, illustrating the method of making a joint at a bend in the same. Figs. 4 and 5 are sectional views showing modified forms of coupling-section. 75

Referring to Fig. 1, which shows my invention adapted for use in a heating stove, A— is a cast-metal fire-pot, circular in form; and B— is a thin flexible pipe bent to form an ascending coil conforming in curvature to the wall of the fire-pot. The coil is wholly inclosed by the fire-pot wall which is cast upon and around the thin pipe while the same is supported like a core in the mold. C— is a coupling-section formed of a short section of strong, heavy pipe having coupling-threads 90 C'— on one end and its other end secured directly to the casting in communication with the inlet terminal of the core-pipe, the fire-pot wall being cast upon and around the coupling-section while the same is supported 95 in the mold in communication with the terminal of the core-pipe. C²— is a coupling-section in the form of an elbow, similarly inclosed by and secured directly to the casting in communication with the exit terminal of 100 the core-pipe.

In Fig. 2 I have shown a rectangular fire-pot D— having its walls cast upon and around the thin core-pipe D'— which extends lon-

gitudinally of the front and both end-walls of the fire-pot. The coupling-sections D²— and D³— are in the form of elbows and are secured directly to the casting in communication with the respective terminals of the core-pipe in the same manner as those shown in Fig. 1. A fire-pot constructed as above described can be cheaply made and easily applied to known forms of heating apparatus; and, in connection with a radiator or hot-water reservoir, can be used for steam or hot-water heating purposes. In bending the thin core-pipe to the form shown in Fig. 2, I cut away a triangular portion of the pipe, as shown at D⁴— in Fig. 3, leaving only a narrow wall D⁵— connecting the pipe-sections on opposite sides of the cut portion. I then bend one of such sections from the position shown by solid lines to that indicated by dotted lines in the latter figure, whereby the several edges of the pipe-sections are brought into contact and the direction of the pipe is changed without the use of couplings and without diminishing the size of the passage-way therethrough. By leaving an unsevered portion D⁵— of the pipe-wall at such joint, the core formed by the angularly-arranged pipe-sections, is made self-supporting in the mold, and disarrangement of the parts prevented. The core-pipe can be made of any kind of sheet, or other form of, metal that will withstand the casting operation, and may be of any desired cross-sectional form. No great care is necessary in joining the longitudinal edges of a seamed pipe, or in forming connections between parts to be inclosed by the casting, such as the joints formed at the bends in the core-pipe shown in Fig. 2, it only being necessary to cover the joints and seams in any known manner, as with core-sand or other composition, to prevent the entrance of the molten metal therethrough in the casting operation, the inclosing metal, when set, completing and protecting the joints. The core-pipe being wholly inclosed by the casting, is supported and strengthened by the inclosing

cast-metal to withstand internal steam or water pressure; and should any portion of the core-pipe be, or become, defective, the inclosing cast-metal would cover and correct such defect. The coupling-sections can be made of any known form or material, preferably of wrought-metal pipe; and may be secured directly to the casting in any known manner.

In Fig. 4, I have shown a metal wall E— cast around the thin core-pipe E'—. The coupling-section E²— is screw-threaded exteriorly, and the wall may be cast around its inner end, or the same may be screwed into a threaded socket in the casting.

In Fig. 5, the wall F— is cast around the thin core-pipe F'—; and the coupling-section F²— is bolted to the casting by means of the screw-bolts F³— passing through a flange F⁴— on the coupling-section, and inserted in the casting. A washer F⁵— may be inserted between the coupling-section and the casting, when desired.

What I claim as new, and desire to secure by Letters Patent, is—

1. The combination with a relatively thin flexible pipe, and a metal wall cast around the same, of relatively thick coupling-sections secured directly to the casting in communication with the respective terminals of the pipe, substantially as described.

2. In a fire-pot for heating apparatus, the combination with a relatively thin flexible pipe, and relatively thick coupling-sections severally contiguous to and communicating with the respective pipe-terminals, of a fire-wall cast upon and around the pipe and the contiguous communicating ends of the pipe and coupling-sections, substantially as described.

In testimony whereof I have hereunto set my hand this 5th day of December, 1893.

ROLAND H. STUBBS.
